UNITED STATES PATENT OFFICE.

CHARLES F. WENSINGER, OF FREMONT, OHIO.

LUGGAGE CARRIER.

Application filed April 5, 1926. Serial No. 99,894.

This invention relates to luggage carriers, one of the objects being to provide a device of this character which can be applied readily to the running board of a motor vehicle 5 and which has a restraining element formed of a flexible material which can be paid out or taken up so as to adapt the carrier to running boards of different lengths and which can flex so as to conform with the 10 contour of the article being held by the carrier. A further object is to provide a structure of this character which is simple and compact in construction and can be adjusted readily to meet the requirements.

15 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

20 In the accompanying drawings the preferred form of the invention has been shown.

In said drawings,

25 Figure 1 is a side elevation of a portion of an automobile to which the present invention is applied.

Figure 2 is an enlarged section on line 2—2, Figure 1.

Figure 3 is an enlarged section on line 3—3, Figure 1.

30 Figure 4 is a section on line 4—4, Figure 3.

Figure 5 is a section on line 5—5, Figure 3.

35 Referring to the figures by characters of reference 1 designates a sleeve having a tubular arm 2 extending laterally from the upper end thereof while another arm 3 is extended laterally from the lower end thereof, these two arms being spaced apart so as to receive between them the running board B of a motor vehicle M. A clamping screw 4 extends through the arm 3 and is adapted to be rotated so as to engage the bottom surface of the running board B and thus hold 40 the sleeve 1 fixedly to the board.

45 A rod 5 is mounted to slide and rotate within the sleeve 1 and has a reduced stem 6 at its lower end surrounded by a coiled spring 7 which serves to yieldingly support the rod. A pin 8 is extended diametrically 50 through the lower end portion of the stem

6 and is adapted to be seated within notches 9 formed in the lower end of the sleeve, thus to hold the rod against rotation as long as it is supported in its uppermost 60 position. A knob 10 or the like can be provided at the upper end of the rod 5 to facilitate depression and rotation thereof by hand. This upper end portion of the rod is journaled within the upper end portion of 65 a brace 11 which extends downwardly and has an inturned portion 12 seated within the arm 2 where it is held by means of a set screw 13 or the like.

70 It is preferred to use two structures such as have been described and secured to each of the rods 5 is one end of a fabric apron or belt 14. Where the carrier is of considerable length it is preferred to use an intermediate support therefor as shown in Figures 1 and 75 3. This support includes a sleeve 15 which is tubular and provided with a tubular arm 16 at its upper end and a clamping arm 17 at its lower end. A clamping screw 18 extends through the arm 17 and is similar to 80 the screw 4. A bolt 19 is mounted in the sleeve 15 and has an eye 20 at its upper end seated within a recess 21 in the sleeve. This bolt is engaged by a nut 22 having a projecting lug 23 adapted to be seated within any 85 one of a series of notches 24 formed in the lower end of the sleeve 15. A rod 25 is extended through the eye 20 and also through the tubular arm 16 and is adapted to be held against rotation by a set screw 26 projecting 90 into a groove 27 formed longitudinally within the rod. Rod 25 has an arm 28 extending upwardly therefrom and to the upper end of this arm is attached a retaining strip 29 the lower end of which has an ear 30 extending 95 outwardly therefrom through which arm 28 projects. Arm 28 and strip 29 form a guide through which the belt 14 can extend as shown and thus be properly supported at an intermediate point.

100 By tightening the nut 22 the rod 25 can of course be held securely against displacement and the set screw 26 will hold it against rotation. It is to be understood of course that the notches 24 and the lug 23 are very small 105 so that the nut can be tightened and these parts will cooperate to prevent it from unscrewing readily.

110 After the sleeve 1 and 15 have been properly positioned upon and secured to the running board B one or both of the rods 5 is depressed so as to disengage the pin or pins

8 from the notches 9. Said rod or rods are then rotated to wind the belt thereon and after the belt has been drawn taut the rods are released and the pins 8 will snap into 5 those notches 9 above them. Thus unwinding of the belt is prevented and said belt will be held taut about the articles retained thereby on the running board.

Obviously with a device such as described 10 it is possible to hold large articles such as bushel baskets and the like on the running board and the belt 14 will extend partly around them and properly hold them in position.

15 Obviously other arrangements of the winding means can be provided without departing from the spirit of the present invention as claimed.

What is claimed is:

20 1. In a luggage carrier the combination with a flexible belt, of means for adjustably connecting and supporting the same relative to a running board or the like, said means including a sleeve, spaced arms for receiving 25 the running board therebetween, means carried by one of the arms and cooperating with the other arm for clamping upon the inserted portion, a brace seated at one end

within one of the arms and extending above the sleeve, a rod slidably and rotatably mounted within the upper portion of the brace and the sleeve, yielding means in the sleeve for holding the rod normally elevated to one position, cooperating means upon the rod and sleeve for holding said rod against rotation when in normal position, said belt being connected to the rod and adapted to be wound thereon. 30 35

2. In a luggage carrier the combination 40 with a flexible belt, of a sleeve, spaced arms integral therewith for receiving a running board therebetween, means carried by one of the arms and cooperating with the other arm for clamping upon an inserted running board, a brace connected to one of the arms and extending above the sleeve, a rod slidably and rotatably mounted within the upper portion of the brace and the sleeve, yielding means for holding the rod normally in one position, and means for holding said rod 45 against rotation when in normal position, said belt being connected to the rod and adapted to be wound thereon. 50

In testimony that I claim the foregoing as my own, I have hereto affixed my signature.

CHARLES F. WENSINGER.
